AUTOMOBILE DECK RACK

William L. Hutchins, 2672 Adie Road,
Hazelwood, Mo. 63042

Filed Dec. 5, 1968, Ser. No. 14,818

Term of patent 14 years

Int. Cl. D12—14

U.S. Cl. D14—27

FIG. 1

FIG. 2

FIG. 3

FIG. 4

FIGURE 1 is a perspective view of an automobile deck rack embodying my new design,

FIGURE 2 is a top plan view of the automobile deck rack as shown in FIGURE 1,

FIGURE 3 is an end elevational view of the automobile deck rack, and

FIGURE 4 is a side elevational view of the automobile deck rack.

The automobile shown fragmentarily and in broken lines is included for illustrative purposes only.

I claim:

The ornamental design for an automobile deck rack, substantially as shown and described.
